ADHESIVE WINDOW SHADE MOUNTING

Charles M. Judd, Cincinnati, Ohio, assignor to
 The Chas. W. Breneman Co., Cincinnati, Ohio,
 a corporation of Ohio

Application March 9, 1951, Serial No. 214,658

3 Claims. (Cl. 160—400)

1

This invention relates generally to window shades and embraces particularly a simple arrangement for securing the upper edge of the shade to the shade roller by the use of pressure-responsive adhesives.

The adhesive bonding structure is intended for replacement shades which are sold without rollers so that the purchaser can attach them quickly and conveniently to the existing rollers at home. This mode of attachment is especially useful in mounting shades formed of synthetic plastic sheets such as vinyl plastic and similar materials which are quite popular for window shade use. However, such materials are soft in texture and cannot be satisfactorily attached to the rollers by tacks or staples as is customary with cloth, paper, or fibre shades. The plastic is quite tough, but it has a tendency, when rolled tightly upon the roller, to be indented or impressed permanently with the protruding heads of the tacks or staples. These are visible in rows across the shade when it is lowered and spoil its appearance.

Bonding the shade to the roller by means of a continuous adhesive strip eliminates this damage and also makes the job considerably easier for the housewife who has difficulty in tacking the edge of the shade straight and smoothly to the roller. Also the plastic sheet does not possess a great deal of resistance to tearing when pierced by tacks or staples, whereas the adhesive strip provides a continuous strong bond between the shade and roller.

One of the primary objects of the invention has been to provide a shade having a pressure-responsive adhesive strip mounted upon its upper edge and presenting a permanently tacky surface for attaching the shade to its roller. This allows the shade to be stretched and aligned with the roller, then bonded by pressing it in place in straight smooth condition.

Another object has been to provide a pressure-responsive adhesive mounting strip having sufficient adhesiveness to bond the shade securely to the roller, but which allows the shade to be stripped cleanly from the roller for replacement with a new shade when necessary.

A further object has been to provide, in connection with a pressure-responsive strip, a facing strip which overlies the tacky surface of the adhesive to prevent air-drying, the facing strip being adapted to be peeled from the adhesive strip prior to mounting the shade in order to provide a clean and fresh adhesive surface which will bond readily to the surface of the roller. The detachable nature of the exposed adhesive coat-

2

ing thus serves to provide the forcible removal of the shade from the roller and also to permit the use of the removable facing strip. The facing strip overlies the entire adhesive strip and marginally overhangs it in order to provide a loose marginal edge which can be grasped readily in order to strip off the facing strip at the time of application.

The adhesive arrangement consists of a strip, 10 preferably of strong paper, having coatings of disparate adhesiveness deposited on opposite sides, the coating of greater adhesiveness bonding the strip to the upper edge of the shade. The facing strip is applied after the adhesive strip is bonded to the shade to preserve its tacky surface. The shade is furnished to the user in this condition and is mounted simply by stripping the facing strip and applying the exposed strip to the shade roller. As noted above, the adhesive coating which bonds the strip to the shade provides a stronger bond than the coating which bonds the facing strip to the adhesive strip so that the adhesive strip is not disturbed when the facing strip is peeled off or when the shade is later peeled from the roller.

Although the bonding of the shade to the roller is sufficiently strong to prevent the shade to be pulled from the roller in normal use, the shade can be stripped off readily by progressively peeling it crosswise from the roller. In other words, when the shade is pulled downwardly, the force tending to detach the shade is resisted by the entire adhesive strip uniformly and the bond is sufficiently great to resist this force, but by 30 peeling the strip progressively across the roller, the bond can be overcome quite easily, leaving the surface of the roller entirely clean so that the new shade can be applied without cleaning the roller. For the same reason, the facing strip can 35 be peeled easily from the adhesive strip, leaving all of the adhesive coating upon the shade and exposing it in fresh tacky condition.

Although the structure is intended particularly for plastic shades, it is also contemplated to apply the pressure-responsive strip to shades formed of cloth, paper and fibrous materials and thereby to facilitate the mounting and dismounting of them in the same manner. Other features and 45 advantages of the invention will be more fully described in the following specification taken in conjunction with the drawings.

In the drawings:

Figure 1 is a general view of a shade and roller 50 combination with the shade secured to the roller.

by means of the pressure sensitive strip of this invention.

Figure 2 is an enlarged fragmentary view similar to Figure 1, but showing a portion of the adhesively bonded end of the shade pulled away from the roller to illustrate the strip arrangement.

Figure 3 is a sectional view taken on line 3—3, Figure 2, further detailing the adhesive bond between the edge of the shade and roller.

Figure 4 is a fragmentary view of the shade before attachment to the roller with a portion of the facing strip peeled back from the adhesive strip preparatory to mounting it upon a roller. The adhesive strip is permanently bonded to the surface of the shade but in this view is shown peeled back to expose the adhesive coating which bonds it to the shade.

Figure 5 is an enlarged exploded view taken on line 5—5, Figure 4, more clearly illustrating the relationship of the adhesive coatings of the adhesive strip illustrated in Figure 4.

Referring particularly to Figure 1 of the drawings, the shade is indicated generally at 10 and its roller at 11. The roller is conventional, being formed preferably of wood and having the usual spring winding mechanism and including end caps 12—12 and pins 13—13 for mounting the roller in the shade brackets. The upper edge of the shade is secured to the roller by means of the pressure sensitive adhesive strip indicated generally at 14, which is provided with a coating of pressure-responsive adhesive material on both sides. This strip is interposed between the edge of the shade and the roller, one adhesive coating securing the strip to the shade and the other securing the strip and shade to the roller.

As above indicated, the shade is intended particularly as a replacement unit for attachment to the existing rollers and the strip permits the average householder in a convenient manner to apply the shades to the rollers by placing the upper edge of the shade upon the roller and bonding it in position by pressing it against the surface of the roller. The pressure-responsive adhesive is of the type which unites securely to the surface against which it is pressed. It is permanently tacky and permits removal of the shade when it becomes worn by grasping an edge and peeling it from the roller.

The adhesive mounting strip is of particular advantage in connection with the shades formed of plastic sheet material because such material has a tendency to split or tear if it is tacked to the shade in the usual manner of cloth shades. The soft pliable nature of sheet plastic allows the outline of the tacks or staples to be impressed into the convolutions of the shade when it is rolled up. Thus, the entire shade will have imparted to its surface at spaced intervals the impression of the tacks or staples and these markings naturally detract from the otherwise smooth and attractive appearance of the shade when it is pulled down.

In its preferred form, the replacement shade is supplied to the user with the double-sized adhesively coated strip mounted permanently upon the upper edge of the shade. In order to preserve the tackiness of the exposed adhesive surface 15, a facing strip 16 (Figure 4) is applied over the exposed coating. This facing strip may be formed of strong paper, Cellophane, or similar material and is slightly wider than the adhesive strip 14 to provide an overhanging loose edge as indicated at 17 (Figure 5). This edge may be grasped by the user to strip the facing from the

adhesive strip as indicated. The facing strip not only prevents air-drying of the otherwise exposed surface, but also prevents dust and dirt from becoming deposited upon it and thus keeps the coating in fresh tacky condition.

The adhesive strip 14 consists of a base strip 18 formed of paper or a plastic material such as Cellophane and has on both sides, a deposit or coating of the pressure-responsive adhesive material. The coating 19, which bonds the strip permanently to the shade, is adhesively stronger than the coating 15 which bonds the shade to the roller. The strip is applied to the edge of the shade by the manufacturer with the facing strip applied over it ready for use. It will be apparent therefore, that both adhesive coatings are protected from air-drying since one coating is permanently sealed between the shade and the adhesive strip while the second coating is temporarily sealed between the adhesive strip and the removable facing strip.

Although the structure is disclosed in connection with a plastic shade, it can be applied to cloth and paper shades with equal facility. In like manner it is not restricted to mounting shades on wooden rollers, but is equally effective in applying shades to rollers formed of fibre and other materials. The pressure-responsive adhesive coatings are of a well known commercial grade which provide a high degree of tenacity once applied to a bonding surface but which, as noted above, are disparate in adhesiveness such that the facing strip can be peeled cleanly, and likewise allowing the shade to be peeled from the roller without the adherence of adhesive patches to the roller.

Having described my invention, I claim:

1. A replaceable window shade unit adapted to be mounted adhesively upon a shade roller comprising, a shade formed of synthetic plastic material, an adhesive strip formed of thin flexible material having a substantial width, the strip having a tacky, pressure-responsive adhesive coating deposited on both sides thereof, the said coatings being of disparate adhesiveness on opposite sides of the said strip, the strip being bonded permanently to the surface of the shade along the upper edge thereof by the coating having the greater adhesiveness, the upper edge of the adhesive strip being flush with the upper edge of the shade adapting the edge to be aligned with the axis of a shade roller for mounting the shade thereon, the other of said coatings being adhesively bondable to the roller upon pressing the upper edge of the shade against the roller.

2. A replaceable window shade unit adapted to be mounted adhesively upon a shade roller comprising, a shade formed of synthetic plastic material, a thin flexible paper strip having a tacky, pressure-responsive adhesive coating deposited on both sides thereof, the said coatings being of disparate adhesiveness on opposite sides of the paper strip, the paper strip being bonded permanently upon the surface of the window shade along the upper edge thereof by the coating having the greater adhesiveness, the upper edge of the paper strip being flush with the upper edge of the shade adapting the edge to be aligned with the axis of a shade roller for mounting the shade thereon, the second of said coatings being adapted to bond the upper edge of the shade to the shade roller upon pressing the same against the surface of the roller, the said coating providing a detachable adhesive bond between the shade and roller which pro-

vides sufficient strength for normal usage, but which allows the shade to be stripped forcibly from the roller by peeling the same progressively across the roller.

3. A replaceable window shade unit adapted to be mounted adhesively upon the periphery of a shade roller comprising a shade formed of thin readily deformable plastic sheet material, an adhesive strip formed of thin pliable sheet material having a substantial width, the strip having a tacky pressure-responsive adhesive coating deposited upon both sides thereof, the said coatings being of disparate adhesiveness on opposite side of the said strip, the upper edge of the adhesive strip being flush with the upper edge of the shade with the strip bonded to the upper margin of the shade by the coating having the greater adhesiveness, the coating of lesser adhesiveness thereby providing an ad-

hesive band of substantial width extending continuously across the upper margin of the shade adapted to be pressed directly against the periphery of a shade roller with the upper edge of the shade aligned with the axis of the roller, thereby securing the margin of the shade directly to the periphery of the roller.
